(57) **CLAIM**

The ornamental design for a clasp lock, as shown and described.

DESCRIPTION

1.1 is a front perspective view of the clasp lock in a locked position, showing our new design;

1.2 is a front view thereof;

1.3 is a back view thereof;

1.4 is a right-side view thereof;

1.5 is a left-side view thereof;

1.6 is a top view thereof;

1.7 is a bottom view thereof;

1.8 is a further perspective view of the clasp lock in an open position.

In the representations of the design dashed lines indicate disclaimed features for which protection is not being sought; The product incorporating the present design is a clasp lock for use for separately connecting parts such as a flap with the body of a bag or a backpack, or the ends of a belt, or the like.

1 Claim, 8 Drawing Sheets
